UNITED STATES PATENT OFFICE.

JAMES RENWICK STEWART, OF TACOMA, WASHINGTON.

GUN-SIGHT.

1,094,265.

Specification of Letters Patent. Patented Apr. 21, 1914.

Application filed December 17, 1913. Serial No. 807,208.

To all whom it may concern:

Be it known that I, JAMES R. STEWART, a citizen of the United States, and a resident of Tacoma, in the county of Pierce and State 5 of Washington, have invented a new and Improved Gun-Sight, of which the following is a full, clear, and exact description.

My invention relates to improvements in sights for firearms, and has reference more 10 particularly to front sights.

An object thereof is to provide a simple, inexpensive and efficient sight of strong construction and contrasting colors, whereby the sight can be used efficiently under different 15 light conditions.

A further object of the invention is to make a perfect connection between the bead and the support for the same so that the vibration of the gun barrel, caused by the discharge of the gun, or any other rough hard 20 usage, will not dislodge the bead from the support.

I obtain the above objects by making a gun sight the support of which is provided 25 with a V-shaped groove into which fits a V-shaped extension of the bead and whereto the same is connected by soldering, or otherwise fastening the bead to the support.

The invention consists of the construction 30 and combination of parts to be more fully described hereinafter and fully set forth in the claims.

Reference is to be had to the accompanying drawings forming a part of this specification, in which like characters indicate 35 corresponding parts in all the views and in which—

Figure 1 is a perspective view of my bead; Fig. 2 is a perspective view of the support 40 for the same, with the V-shaped groove; Fig. 3 is a transverse section of the support through the V-shaped groove on line 3—3, Fig. 4; Fig. 4 is a section on line 4—4, Fig. 3; Fig. 5 is a transverse section of the support, similar to Fig. 3, with the bead soldered thereto; Fig. 6 is a side view of the upper portion of the gun sight; and Fig. 7 is a plan view of the same.

Referring to the drawings, 8 represents 50 the base of the support of the gun sight, which is made to fit the barrel of the firearm. The said base is provided with an extension 9 transverse thereto and integral therewith and adapted to be positioned in 55 the longitudinal axis of the barrel of the firearm. The upper portion of said exten-

sion 9 is reduced, as shown at 10, and then enlarged in a substantially longitudinal cylindrical portion 11 in which a longitudinal V-shaped groove 12 is formed. The bottom 13 of the groove is made to rise from the rear end of the extension toward the front of the same, the said groove ending substantially in the middle of the cylindrical portion 11, with the said bottom 13 of the groove curved at the said ending, so as to offer a greater resistance to the wedge-shaped portion 14 of the bead 15 fitting into the groove 12.

The V-shaped groove 12 and the wedge 70 portion 14 of the bead 15 have a large contacting surface for the solder which connects the bead to the support. Due to the formation of the V-shaped groove or notch, the upper portion of the bead extends substantially over half of the length of the cylindrical portion 11 of the support; and as the bead is of a metal which is a good reflector of light, a large illuminated area will be formed at the most appropriate place on 80 the bead, that is, at its upper part.

From the above it will be seen that the aim of my invention is to secure the bead to the support so that the same cannot be loosened therefrom by the vibration of the 85 gun shot, and also to obtain a large illuminated area at the upper part of the bead on the support.

Having thus described my invention, I claim as new and desire to secure by Letters Patent:

1. In a gun sight, a support having a longitudinally disposed V-shaped notch; and a bead having a wedge-shaped extension fitting snugly into said notch and integrally 95 secured thereto, said bead being formed of a good light reflecting substance.

2. In a gun sight, a support having a longitudinal cylindrical portion; a longitudinal V-shaped notch extending from the rear of said support substantially to the middle of said portion, the bottom of said notch rising from the rear to the front and being curved at the front end thereof; and a bead having a wedge-shaped portion fitting 100 snugly into said notch and integrally secured thereto, said bead forming a part of said cylindrical portion whereby said bead presents a large reflecting surface at its upper part.

3. In a gun sight, a support having a substantially cylindrical portion at its up- 110

per end, the rear part of said portion being formed by a bead integral therewith, said bead being a good reflector for light and having a wedge-shaped extension, and said 5 cylindrical portion having a V-shaped groove engaging said extension.

In testimony whereof I have signed my

name to this specification in the presence of two subscribing witnesses.

JAMES RENWICK STEWART.
